UNITED STATES PATENT OFFICE.

WILHELM BACHMANN, OF ZURICH, SWITZERLAND.

LOCK FOR CABINET DOORS AND THE LIKE.

Application filed December 30, 1922. Serial No. 610,007.

To all whom it may concern:

Be it known that I, WILHELM BACHMANN, a citizen of the Swiss Republic, residing at Zurich, Switzerland, have invented 5 certain Improvements in Locks for Cabinet Doors and the like, of which the following is a specification.

This invention relates to a lock of the kind having two bolts which are shot in 10 opposite directions, and its object is to produce a non-obstructive lock which can be fitted on cabinet doors or the like without recessing the same except as far as required for the introduction of the key.

15 This object is achieved by means of the invention which consists in the provision of a shallow elongated casing containing a revoluble barrel, two spring-pressed bolt-operated slides, and two links which are pivoted 20 to the barrel and which bear against the slides, the latter being shot or retracted by half a revolution of the barrel and retained, in one position by the overlapping of the 25 links across the barrel and in the other position by the mutual abutment of the elements at a point of the movement beyond the dead centre of the links.

Fig. 1 of the accompanying drawings represents a sectional view of a cabinet door 30 to which the lock is attached,

Fig. 2, a view of the lock casing with the cover removed,

Fig. 3, a sectional view of the lock casing,

Fig. 4, a cross-section on the line A—A 35 of Fig. 3,

Fig. 5, a cross-section on the line B—B of the same figure,

Fig. 6, a view of the key,

Fig. 7, a view of one of the guide plates,

40 Fig. 8, a view of the interior of the lock showing the bolt-operating slides in retracted position,

Fig. 9, a similar view showing the slides in shot position,

45 Fig. 10, an enlarged view of the revoluble barrel and its links, and

Fig. 11, a view at right angles to Fig. 10.

The lock casing is composed of an elongated plate 1 having raised edges 2 on which 50 fits a cover 3. The latter carries a centrally disposed cylinder 7 which contains a rotatable guide block 9 for a flat key 20 having a handle 21. The key is admitted through a slot 8 in the block behind which

55 there is a ward plate or a plurality of plates 10 through slots 12 (Fig. 4) in which the

key must pass. Each slot 12 has a central circular enlargement 11 allowing the key to turn when notches 22 in the key register with the plates. The inner end of the cylinder 7 receives the reduced portion 18 of a revoluble barrel 16, the latter being accommodated within the lock casing and guided therein by two plates 13 which conform with the shape of the casing, each plate having a central aperture 17 in which to receive the barrel. There is in the portion 18 of the barrel a diametral slit 19 into which the key 20 is admitted for turning the barrel. This slot is flared radially outwards so as to 60 allow a slight movement of the key relative to the barrel. Thus, without operating the lock mechanism, the key can be engaged to the ward plate or plates 10 and serve as a handle for opening and shutting the door. 65

Between the plates 13 two slides 28 are arranged, one at each end of the lock casing. The plates 13 are formed with recesses 31 in which to accommodate two coil springs 30, each spring being adapted to 70 bear with one end against a shoulder 29 on one of the slides 28 and with the other end against shoulders 32 on the plates 13. Thus the slides 28 will be urged by the springs 75 towards the barrel 16. The latter is formed with two segmental, circumferential recesses 23 (Fig. 11) within each of which a link 25 is pivoted. Each link has at one end a head 36, which receives the pivot pin 24 and at the other end a head 26 which is in 80 pivotal engagement with the inner circular portion 27 of an otherwise triangular notch in one of the slides 28. The links control the position of the slides. Fig. 8 shows the slide contracted; the links 85 overlap across the barrel and no further contracting movement is possible. The slit 19 of the barrel 16 is in alignment with the key slot in the plate or plates 10 so that the key can be introduced 90 for opening the lock. By a turn on the barrel through 90°, the slides 28 will be shot. In this position, which is shown in Fig. 9, the slides will be retained by the links which, having passed the dead centre, tend 95 to continue the movement of the barrel but are prevented from so doing by abutment against the edges which confine the recesses in the slides and in the barrel.

The lock casing is held together by rivets 100 4 and is secured to the inner face of a cabinet door 6 or the like which is simply drilled 105

to admit the cylinder 7. The fastening screws 5 and the rivets 4 pass through elongated slots 15 in the plates 13 and in the slides. Extensions 33 of the slides are admitted through slots 14 in the ends of the casing, and these extensions are connected by pivot pins 35 to bars 34 which operate the lock bolts, one at the top and the other at the bottom end of the door.

10 The different parts of the lock can be stamped out of sheet metal, and a very cheap and efficient lock will thus be obtained.

I claim:—

1. A key-operated lock for cabinet doors and the like, comprising a shallow elongated casing, a centrally disposed cylinder projecting from said casing at right angles, a guide block for the key arranged rotatably within said cylinder, a revoluble barrel arranged within the casing, said barrel having a reduced portion projecting into said cylinder for engagement with the key, two bolt-operating slides arranged within and at opposite ends of the casing, springs tending to urge the slides towards the barrel, and links pivoted eccentrically to the barrel and supporting the slides so that the latter can be shot or retracted by half a revolution of the barrel, one end position of the barrel being determined by the overlapping of the links across the barrel and the other end position by the abutment of the link flanks against the slides at a point of the movement beyond the dead centre of the links.

2. A key-operated lock for cabinet doors and the like, comprising a shallow elongated casing, a centrally disposed cylinder projecting from said casing at right angles, a guide block for the key arranged rotatably within said cylinder, a slotted ward plate arranged in said cylinder so as to engage

notches in the key when the latter is turned and prevent a withdrawal of the same, a revoluble barrel arranged within the casing, said barrel having a reduced portion projecting into said cylinder, said reduced portion being formed with a diametral slit for engagement with the key, said slit being shaped so as to allow a slight rotation of the key for engagement with said ward plate without affecting the barrel, two bolt-operating slides arranged within and at opposite ends of the casing, springs tending to urge said slides towards the barrel, and links pivoted eccentrically to the barrel and supporting the slides so that the latter can be shot or retracted by half a revolution of the barrel, one end position of the barrel being determined by the overlapping of the links across the barrel and the other end position by the abutment of the link flanks against the slides at a point of the movement beyond the dead centre of the links.

3. A lock for cabinet doors and the like, comprising a shallow elongated casing, two bolt-operating slides arranged inside and at opposite ends of said casing, springs tending to urge the slides towards the center of the casing, a key-operated revoluble barrel arranged between the ends of the slides in the center of the casing, and links pivoted eccentrically to the barrel and resting in notches in said slides so that the latter can be shot or retracted by half a revolution of the barrel, one end position of the barrel being determined by the overlapping of the links across the barrel and the other end position by the abutment of the links against the edges of the slide notches at a point of the movement beyond the dead center of the links.

WILHELM BACHMANN.
